UNITED STATES PATENT OFFICE.

DANIEL H. PAYNE AND EVYLEN C. WOODWORTH, OF BOYES SPRINGS, CALIFORNIA.

CLOTHES-DRIER.

1,178,343.

Specification of Letters Patent.

Patented Apr. 4, 1916.

Application filed June 12, 1915. Serial No. 33,721.

To all whom it may concern:

Be it known that we, (1) DANIEL H. PAYNE and (2) EVYLEN C. WOODWORTH, (1) citizen of the United States, and (2) 5 subject of the King of Great Britain, residing at Boyes Springs, in the county of Sonoma and State of California, have invented certain new and useful Improvements in Clothes-Driers; and we do hereby declare 10 the following to be a full, clear, and exact description of the invention, such as will enable others skilled in the art to which it appertains to make and use the same.

Our invention is an improved clothes 15 drier for attachment to and suspension from a ceiling or other overhead support; the object of our invention being to provide an improved device of this character which embodies a longitudinally extensible sus- 20 pending standard, a rack carried by and revolvably connected to the lower end of the standard so that the rack may be readily turned, and means to raise and lower the rack at will so that clothes or other articles 25 to be dried may be readily placed on the rack when the same is lowered, the rack may be readily turned to enable clothes to be attached thereto or taken therefrom at any point and so that the rack may be 30 raised, when loaded, and arranged out of the way and to permit free passage under the rack.

One object of the invention is to provide an improved suspending standard which 35 comprises telescopically arranged tubular elements.

Another object is to effect improvements in the construction of the rack.

With the above and other objects in view 40 the invention consists in the construction, combination and arrangement of devices hereinafter described and claimed.

In the accompanying drawings: Figure 1 is a side elevation of a clothes drier con- 45 structed in accordance with our invention, showing the same in lowered position in full lines and in raised position in dotted lines. Fig. 2 is a vertical sectional view of the same, in lowered position. Fig. 3 50 is a similar view of the same in raised position. Fig. 4 is a detail elevation of the same in raised position. Fig. 5 is a detail plan of the rack. Fig. 6 is a detail sectional view on the plane indicated by the 55 line 6—6 of Fig. 3. Fig. 7 is a detail ele-

vation, partly in section, of one of the radial rack arms and of one of the wire securing bolts. Fig. 8 is a detail plan of the attaching block and of the upper end of the suspending standard. Fig. 9 is a detail vertical sectional view of the same.

In accordance with our invention we provide a revoluble rack 1, which comprises a hub member 2 and a series of radially arranged arms 3. The hub member is in practice a casting, comprising a central tubular portion 4, a lower head 5 formed with radially arranged upwardly inclined arms 6, and an upper head 7. The diameter of the lower head is somewhat greater than that of the upper head. The inner ends of the arms 3 are fitted between the heads, so that said arms 3 bear on the arms 6 of the lower head and their inner ends abut against the central portion 4 of the spider. Each rack arm 3 is secured to one of the hub arms 6 by means of a bolt 8. Owing to this construction of the hub member and the arrangement of the rack arms, the latter while being very securely and strongly fastened to the hub member may be readily removed therefrom when desired. Each rack arm has a series of openings 9, suitably spaced apart, and of which any desired number may be provided, and lines 85 10, which may be of such material as an ordinary clothes line, are passed through the said openings 9, arranged in spaced relation and parallel with each other, and serve to connect the rack arms 3. Articles 90 of clothing or the like, for drying, may be hung both on the rack arms 3 and on the lines 10, and hence the rack is of maximum capacity and a large number of articles may be hung thereon and dried at one time, 95 as will be readily understood.

If preferred the lines may be wires and in this event the wire lines are placed in recesses 11 in the upper sides of the rack arms 3 and detachably held in place by 100 bolts 12, as shown in detail in Fig. 7.

An attaching block 13 is provided which may be readily secured to a ceiling 14 or other overhead support by means of screws 15 or other suitable devices. The attaching block is provided with a vertical central opening 16 and in the upper side of the attaching block is a counterbore or recess 17.

The suspending standard 19 is longitudinally adjustable, so that it may be length- 110

ened and shortened at will and comprises a series of telescopically arranged tubular members. As here shown said suspending standard comprises a tubular upper member 19, a tubular lower member 20 and a pair of tubular intermediate members 21—22. Each of the said tubular members is provided at its upper end with an outwardly extending bead or flange and at its lower end with an inwardly extending bead or flange, and said tubular members are progressively each of less diameter than the next and said members are telescopically fitted, one within another, so that the said suspending standard may be readily extended or shortened, as desired. The upper end of the upper member 19 is fitted in the opening 16 of the attaching block and the outturned flange or bead 23 of said members bears in the bottom of the counter-sink or recess 17, as shown in Fig. 9, so that said upper member 19 is securely attached to said attaching block. A pulley 24 is mounted, as at 25, for rotation in a casing 25^a which is suspended from a plate 25^b on the upper end of the tubular member 19. The inturned flange bead of said upper tubular member is shown at 26.

The member 21 is provided in addition to its outturned upper flange 27 and its inturned lower flange 28 with a stop bead or flange 29, which may be rolled therein, or otherwise suitably produced and which, when the standard is extended or lowered, bears on the flange 26 as shown in Fig. 2. The member 22 is similarly constructed, its upper outturned flange being indicated at 30, its lower inturned flange at 31 and its stop flange at 32. The upper, lower and stop flanges of the lower member 20 are respectively indicated at 33, 34 and 35.

A bolt 36 extends through the lower tubular member 20 and projects below the same, its lower end extending through the central bore of the tubular member 4 of the rack hub, so that the rack is pivotally mounted on the lower end of the bolt and may be revolved at will. A nut 37 is screwed to the lower end of the bolt to bear under the hub of the rack and support the same, a washer 38 being interposed between the lower end of the tubular member 20 and the upper side of the hub of the rack, as shown.

To raise and lower the rack and shorten or extend the suspending standard we provide a suitable cord 39 which passes over the pulley 24, and a second pulley 40, which is mounted at a suitable distance from said pulley 24 and one end of this cord extends down through the telescopically constructed and arranged suspending standard and is attached to an eye 41 at the upper end of the bolt. When the rack is raised, which may be done by drawing down on the outer end of the cord 39, said cord may be se-

cured by a suitable cleat, or other device, to support the rack in raised position, the weight of the rack when in raised position, being imposed on said raising and lowering cord. It will be understood that by releasing the cord the rack by its own weight will move downwardly, the suspending standard being extended automatically as the rack is lowered. Stops 20^a limit the upward movement of the standard members and prevent them from becoming disconnected.

What we claim is:

1. In a clothes drier of the class described, a telescopically arranged standard comprising tubular members each having an outturned flange at its upper end, an inturned flange at its lower end, a stop flange on its outer side spaced from its upper flange and adapted to bear on the inturned lower flange of the member in which it is fitted when the standard is extended, an attaching member secured to the upper end of the upper tubular member, a bolt extending through and below the lower tubular member, a rack revolvably mounted on the lower portion of the bolt, and a raising and lowering cord attached to the upper end of the bolt and partly arranged in said standard, and direction pulleys for said cord.

2. A clothes drier of the character described comprising a longitudinally extensible vertically arranged suspending standard having a plurality of tubular telescopically fitted members, an attaching device at the upper end of the upper tubular member, a bolt extending through and below the lower tubular member, a rack revolvably mounted on the lower portion of the bolt, a raising and lowering cord attached to the upper end of the bolt and partly arranged in said standard, and direction pulleys for said cord.

3. A clothes drier of the class described comprising a longitudinally extensible vertically arranged suspending standard having a plurality of tubular telescopically fitted members, said members having inturned flanges at their lower ends, outwardly extending flanges on the upper ends of all of the members, stop flanges on certain of said members, said stop flanges being arranged in spaced relation to the outturned flanges of the members, and a raising and lowering cord attached to the lower member.

4. A clothes drier of the class described comprising a longitudinally extensible vertically arranged suspending standard having a plurality of tubular telescopically fitted members, an outwardly extending flange at the upper end of the upper member, an attaching block having an opening through which passes the upper end of the upper member, said block having in its upper sides a counter bore to provide a shoulder upon which rests the flange of the

upper member, a plate mounted in the counter bore and resting upon the upper end of the upper member, a pulley carried by said plate and located in the upper end 5 of the upper member, a raising and lowering cord secured at its lower end to the lower member, said cord passing upwardly through the member and over the pulley, the cord then passing out beyond the attaching

block through an opening therein, and a 10 rack carried by the lower member.

In testimony whereof we affix our signatures in presence of two witnesses.

DANIEL H. PAYNE.

EVYLEN C. WOODWORTH.
